JOSEPH M. KERN, OF OSWEGO, NEW YORK.

STEAM-ENGINE.

1,301,571.

Specification of Letters Patent. Patented Apr. 22, 1919.

Application filed October 24, 1918. Serial No. 259,464.

To all whom it may concern:

Be it known that I, JOSEPH M. KERN, a citizen of the United States of America, and resident of Oswego, in the county of Oswego, in the State of New York, have invented new and useful Improvements in Steam-Engines, of which the following, taken in connection with the accompanying drawings, is a full, clear, and exact description.

10 This invention relates to certain improvements in steam engines and refers more particularly to the construction of the piston as used in large, high powered locomotives in which the great weight of the piston and 15 high pressure of the steam contribute to produce excessive wear and frequent breakage of the packing-rings commonly employed in pistons of this type resulting not only in a considerable waste of power and 20 fuel and loss of schedule running time but also necessitates the withdrawal of the impaired engine from use for greater or less periods in order to make the necessary repairs and requires a number of engines to 25 be held in reserve for use in such emergencies, all of which adds materially to the operating expenses.

The main objects therefore of my present invention is to provide simple and efficient 30 means for obviating, to a great extent, these difficulties and for materially increasing the life and working efficiency of the pistons of this type, first, by substantially balancing the pistons more nearly co-axial with the 35 bore of the cylinder; second, by automatically equalizing the steam pressure at the inside and outside of the packing-ring immediately upon the exposure of either end thereof to the steam inlet-ports and, third, 40 by using a single relatively long packing-ring extending the major portion of the length of the piston so as to better resist the angular strains to which it is subjected by the sudden application of high steam pressure to either end thereof as it is exposed 45 to the corresponding intake-port.

Other objects and uses relating to specific parts of the piston will be brought out in the following description.

50 In the drawings:

Figure 1— is a longitudinal vertical sectional view of a portion of a locomotive cylinder and piston movable therein, the piston being shown by full lines at the limit 55 of its stroke in one direction and by dotted

lines at the limit of its stroke in the opposite direction.

Fig. 2— is a transverse vertical sectional view through the piston and adjacent portions of the cylinder showing a part of one of the intake-ports.

Fig. 3— is a perspective view of the split packing ring forming a part of the piston.

In order that my invention may be clearly understood, I have shown a cylinder 1— as provided with the usual end heads 2— and 3— and steam-inlet ports 4—, the latter being controlled by a valve 5— partly shown in Fig. 1—.

The piston 6— is reciprocally movable in the bore of the cylinder 1— and comprises a head or collar 7— and a split ring 8— spring-pressed against the inner walls of the cylinder by coiled springs 9—.

The piston-head or collar 7— is firmly secured to the tapered end of a piston-rod 10— and is provided with an annular channel or groove 11— in its periphery and extending the major portion of the length thereof to relatively short distances from the ends of the head or collar for receiving the ring 8— of corresponding length, said head being also provided with a series of, in this instance, four radial pockets 12— in equally spaced relation circumferentially and extending inwardly from the annular recess or channel 11— for receiving the coiled springs 9—.

The steam-inlet ports 4— open into opposite ends of the bore of the cylinder at the upper side thereof, the stroke of the piston being such as to cause the ends of the ring 8— to alternately register with the corresponding ports as the piston reaches the limits of its strokes in reverse directions, that is, relatively small portions of the ends of the ring are caused to be moved beyond the inner walls of their respective ports 4— to assure uniform wear of that portion of the bore of the cylinder between said ports.

The upper portions of the ring 8— which project beyond the inner walls of the ports 4— when the piston is at the limit of its stroke in either direction are provided with radial passages 13— therethrough to permit the entrance of the high pressure steam to the inner side of the ring when either end of the ring is registered with the corresponding port 4— thereby equal-

izing or balancing the steam pressure internally and externally of the ring.

The distance between the ports —4— is substantially equal to the length of the stroke 5 of the piston plus the distance between the passages —13— in the ring —8— so that when the piston reaches the limit of its movement in one direction the corresponding passage —13— will be registered with 10 the adjacent port —4— and when it reaches the limit of its movement in its opposite direction, the other passage —13— will be registered with its corresponding port thereby preventing excessive inward radial strains 15 upon the ring by the sudden impact of the high pressure steam from the ports —4— against the adjacent portions of the periphery of the ends of said ring when the piston reaches the limit of its movement in either 20 direction at which time the high pressure steam is suddenly admitted to the corresponding end of the piston by the shifting of the valve —5—.

By extending the ring —8—, the greater 25 portion of the length of the piston affords a relatively long bearing thereof against the walls of the cylinder and enables it to better resist the tendency to angular or transverse tilting movement due to the sudden impact 30 of the high pressure steam against the periphery of the ends thereof as said ends are alternately registered at their respective ports, and also serves to guide the piston more evenly in its axial movement thereby 35 effecting a more uniform wear of the ring and bore of the cylinder from end to end without liability of excessive friction or cutting of either of those parts.

It will be observed upon reference to Fig. 40 —2— that the radial passages —13— are formed only in the upper side of the ring or in that side which is adjacent the steam inlet ports —4— and that the radial coiled springs —9— exert equal pressure upon opposite halves of the ring to hold them in 45 contact with the walls of the bore of the cylinder —1—, thus leaving a sufficient space between the inner face of the ring and base of the annular groove —11— for the entrance and distribution of the steam entirely 50 around the inner face of the ring for balancing purposes previously referred to.

As shown more clearly in Fig. —3—, the ring —8— is divided diagonally at —14— 55 through diametrically opposite sides thereof and, if desired, the inner faces of the adjacent ends of the ring sections at one side may be provided with registering grooves —15— intersecting the adjacent diagonal 60 line of division for receiving a key —16— by which those ends may be held against separation when the ring-sections are assembled in the groove —11— of the piston, key —16— also serving to enter a groove 65 —17— in the adjacent portion of the base

of the annular groove —11— to assure the proper positioning of the passages —13— relatively to the ports —4—.

The springs —9— in addition to their function of pressing the ring-sections against the walls of the cylinder also serve to keep the main body —7— of the piston centrally within the bore of the cylinder or co-axial with the axis of the stuffing-box, as —18— in which the piston-rod —10— is guided, the two lower springs, Fig. —2—, serving to counteract the weight of the main body —7— of the piston thereby reducing the liability of sagging of the end of the piston-rod to which it is secured and to that extent assisting in keeping said rod and main body of the piston co-axial with the bearing in the stuffing-box —18— through which the rod slides which assures a steady action of the piston and reduces wear of the rod and stuffing-box to a minimum and adds materially to the life of the piston.

The springs —9— are preferably located midway between the ends of the ring —8— and between the opposite sets of passages —13— so as to cause all portions of the rings to be pressed against the walls of the cylinder with equal force without in any way interfering with free passage of steam through the ports —13— when the latter are 95 alined with their respective ports —4—.

The operation of my invention will now be readily understood upon reference to the foregoing description and the accompanying drawing and while it is particularly useful in connection with the pistons of large locomotive cylinders of high power, it is evident that it may be used on the pistons of steam pumps and other apparatus.

What I claim is:

1. In a steam engine, the combination of a horizontally extending cylinder having the usual steam inlet ports, a piston reciprocally movable in the cylinder and provided with an annular recess extending the greater portion of its length, a split packing ring fitting said recess and spring-pressed against the walls of the cylinder, said ring having radial openings therethrough near the ends thereof to alternately register with the steam-inlet ports for equalizing the steam pressure on the inner and outer sides of the ring as they are registered with their respective ports.

2. The combination of a steam cylinder 120 having inlet-ports in opposite ends of one and the same side, a piston reciprocally movable in the cylinder and provided with an annular recess, a split-packing ring engaging the end walls of the recess and provided with radial openings therethrough in spaced relation axially to alternately register with the corresponding inlet-ports as the piston reaches the limits of its strokes in reverse directions.

3. In a steam engine, the combination of a substantially horizontal cylinder having radial ports in the ends of the upper side thereof, a piston reciprocally movable in the cylinder and comprising a main body having an annular recess and a packing-ring fitted in the recess, the upper side of said ring being provided near its ends with radial passages adapted to alternately register with said ports as the piston reaches the limits of its movements in reverse directions.
4. In a steam engine, the combination of a substantially horizontal cylinder having radial ports in the ends of the upper side thereof, a piston reciprocally movable in the cylinder and comprising a main body having an annular recess and a packing-ring fitted in the recess, the upper side of said ring being provided near its ends with radial passages adapted to alternately register with said ports as the piston reaches the limits of its movements in reverse directions, and springs interposed between the ring and main body of the piston for holding said ring in contact with the walls of the cylinder and for supporting the main body co-axial with the bore of said cylinder.
5. In a steam engine the combination of a cylinder having inlet-ports in the opposite ends of one side, a piston reciprocally movable in the cylinder and comprising a main body having an annular recess extending the

greater portion of its length and a packing-ring fitted in said recess, said ring being provided near its ends with radial passages adapted to alternately register with said ports as the piston reaches the limits of its movements in reverse directions.

6. In a steam engine, the combination of a cylinder having inlet-ports in the opposite ends of one side, a piston reciprocally movable in the cylinder and comprising a main body having an annular recess extending the greater portion of its length and a packing-ring fitted in said recess, said ring being provided near its ends with radial passages adapted to alternately register with said ports as the piston reaches the limits of its movements in reverse directions, the main body of the piston being provided with radial pockets in equally spaced relation circumferentially, and coiled springs seated in said pockets and having their outer ends engaged with the inner faces of the ring for holding said ring in engagement with the walls of the cylinder and also for keeping the main body of the piston co-axial with the bore of the cylinder.

In witness whereof I have hereunto set my hand this 11th day of October, 1918.

JOSEPH M. KERN.
